ELECTRIC FURNACE

Henry E. Stauss, East Orange, and Joseph Ogden,
Kearny, N. J., assignors to Baker & Co., Inc.,
Newark, N. J., a corporation of New Jersey

Application June 29, 1935, Serial No. 29,110

1 Claim. (CL 13—1)

This invention relates to a novel and improved form of electric furnace, the novel features of which will be best understood from the following description and the annexed drawings, in which we have shown selected embodiments of the invention and in which:

Fig. 1 is a top plan view of one form which the invention may take;

Fig. 2 is a vertical elevation of the device shown in Fig. 1, parts being broken away and shown in section;

Fig. 3 is a vertical sectional view approximately on the line 3—3 of Fig. 1;

Figs. 4 and 5 are views similar to Fig. 3 but showing different forms of the invention.

Referring first to Figs. 1, 2, and 3, the invention is shown as comprising a crucible 1 of any suitable heat-conducting material and which is shown as having an open top. In operation, a lid of any suitable form may be used to cover the crucible, but since the lid itself does not affect the invention claimed herein, it has been omitted.

The crucible is shown as being disposed within a container 2 containing insulating material 3 closely and compactly surrounding the crucible and covering the walls thereof. Between the insulating material and the walls of the crucible is placed an electric heating element 4 which is wound around the crucible and may be embedded in a thin coat of cement 4', as alundum or the like, which serves the dual purpose of distributing the heat from the heating element uniformly along the crucible between the turns of the winding, and of protecting the winding from contamination by the insulating material. The element 4 may be made of any suitable material adapted to form an electric resistor, although we have found that a wire of platinum or platinum-rhodium is preferable for the purpose.

We are aware that crucibles of suitable material have been wound with electric heating elements or have been heated by other means. Usually such crucibles have had to be lifted while fully loaded and while hot, and have had to be tilted for pouring. It is our belief that the shearing stresses set up in the material of the crucibles by the handling have been responsible for the failure by breakage of the crucibles.

The above difficulty we have overcome by placing the crucible in a container and supporting it thoroughly with the insulating material, thus relieving the crucible from the shearing stresses which the ordinary crucible has to stand.

We are also aware that it has been hitherto proposed to construct crucibles heated by electric

elements and surrounded by insulation, but such arrangements as have been suggested have presented certain difficulties in the pouring of molten material from the crucible. One attempt to overcome such difficulties, as shown in the patent to Northrup 1,551,766, proposed to provide a pouring spout extending from the crucible to the outer wall of the container. However, the molten material passing over the extended surface of the pouring spout tends to coagulate because of the chilling effect of the extended surface.

We have overcome the difficulties in pouring a molten material from a crucible wound with electric heating elements and fully supported by the insulation by providing a pouring lip directly at one edge of the container, such a lip being exemplified by the lip 5 which, it will be seen, is directly adjacent the upper edge of the container wall 6. The small portion of the lip which extends above the upper edge of the wall 6 may be supported by cement 7, which in fact is shown as extending completely around the top edge of the crucible.

From the lip 5 extends downwardly and inwardly towards the center of the container one wall 8 of the crucible.

Looked at another way, the crucible is placed in the container with its normally vertical axis tilted to the vertical sufficiently to bring one wall at the top edge substantially to the top edge of the container wall. Then the top edge of the crucible may be cut off so as to make it horizontal, or a crucible of proper shape may be used, as indicated in Figs. 2 and 3, and a suitable lid may be used to cover the crucible, if desired, although oftentimes with electric heating a lid is found unnecessary.

It will be seen that the insulating material supports the wall 8 as well as all the rest of the crucible, so that when pouring, no additional strains are placed on the material of the crucible. At the same time, the molten material in the crucible may be poured directly from the crucible without having to pass over an extended surface which will cause it to be chilled. The small pouring lip, being formed of the same material as the wall 8, and in fact being a part of that wall, will be maintained hot by the heating element, and it does not extend away from the crucible far enough to be chilled and thus chill the contents of the crucible during its pouring. Thus the molten material will be kept molten until poured.

For convenience of handling, particularly

where the device is small and used for melting small quantities of metal, we provide a handle 9 of wood or other suitable insulating material, which may be secured to the container by means 5 of fasteners 10, and which may be further insulated from the container by a sheet 11 of mica and a sheet 12 of asbestos. The container 2 may conveniently be made of sheet metal. The handle may be used as a conduit for a cable 13 containing two conductors 14 attached to binding posts 15 on the mica sheet, and to these binding posts may be attached the electric element 4 used for winding the crucible.

In Fig. 4 is shown a form of crucible 16 which 15 is cylindrical in form but which, like the other forms of Figs. 1, 2, and 3, is provided with a pouring lip 17 over the top edge of the wall 6 of the container. From this lip 17 extends downwardly and inwardly towards the center of the receptacle 20 a wall 18 of the crucible, and here again it will be seen that the inner surface of this wall is substantially continuous to the pouring lip, thus obtaining the advantages outlined above. Otherwise, the construction of the form shown in Fig. 25 4 follows closely that shown in Figs. 1, 2, and 3.

Referring now to Fig. 5, we have shown there-in how the invention may be employed with replaceable crucibles. The crucible 19 follows generally the form shown in Fig. 4 except that the 30 inner surface 20 thereof is adapted to receive a closely fitting second crucible 21 having a pouring lip 22 closely adjacent the top edge of the wall 6. The top edge of the crucible 21 may be protected with cement 7 as in the other embodiments shown, but this cement may be easily bro-

ken away when the crucible 21 is to be removed.

The device in any form shown comprises a compact and economical electric furnace which avoids some of the difficulties of the prior art, as outlined above. Over one hundred melts are 5 made regularly in one crucible without breakage or apparent wear. At the same time, the furnace is easy to handle, operates at small cost, and permits pouring of the metal without removing the crucible and without coagulation during 10 pouring.

While we have shown the invention as embodied in certain specific forms, those forms have been selected purely as illustrative, and we do not intend to limit ourselves except by the appended 15 claim.

We claim:

In an electric furnace, a container having a vertically extending wall, a crucible of heat-conducting material disposed within said container 20 and having one wall thereof inclined to the vertical, with its upper edge substantially at the upper edge of the container wall and its lower portion spaced from said container wall, said crucible wall extending continuously upwardly 25 to its said upper edge, whereby said upper edge of the crucible wall forms a spoutless pouring lip, insulating material disposed in said container and supporting said inclined crucible wall, and an electric heating element arranged to heat the 30 crucible wall, whereby said crucible wall is thoroughly supported and heat may be imparted to and retained by said lip.

HENRY E. STAUSS.
